UNITED STATES PATENT OFFICE

PHILIP D. SPAETH, JR., OF CLEVELAND, OHIO, ASSIGNOR TO THE PHILAD COMPANY,
OF CLEVELAND, OHIO, A CORPORATION OF OHIO

COVERING FOR HAIR WAVING

Application filed February 18, 1929. Serial No. 340,768.

This invention relates to the waving of hair upon the human head and more particularly to a covering which is applied to a strand of hair during a waving process. 5 One well known process of producing lasting or "permanent" waves consists of winding a flat strand of hair spirally, one turn over another, upon a rod and then treating the hair with a solution, generally alkaline, and 10 subjecting it to heat to produce steam and cause the hair to take a set in its wound shape. This process is carried on by covering a wound strand of hair with a layer of absorbent material containing a treating solution, which may in turn be covered with a 15 moisture retaining envelope, a metallic guard or the like, and the covered strand is enclosed within an electric heater of one or more sections and having a longitudinal slot 20 through which the hair passes from the scalp. The interior of the heater is generally of cylindrical shape while the coil of hair is somewhat irregular in shape, usually being thicker at the middle of the curler rod even 25 when this is made smaller in diameter at this point than at its ends. Consequently, at some places along the wound strand the heater presses the absorbent material against the hair while at other places the heater is 30 spaced away from the absorbent material and partially heat-insulated from it by the intervening air. This condition, of course, causes some parts of the strand to be subjected 35 to much more heat than others, and prevents all parts of the strand from being uniformly 40 waved. Also, when several layers of covering materials are used, as when a sheet of waxed paper or the like is used to cover the absorbent material, added time and labor are consumed in their application.

An object of the present invention is to provide an improved covering for a wound strand of hair which will eliminate the disadvantages of prior coverings.

45 Other objects will hereinafter appear.

The invention will be better understood from the description of one practical embodiment thereof, illustrated in the accompanying drawings, in which:

50 Figure 1 is a perspective view of a pad or

covering wrapper before being applied to the hair;

Figure 2 is a perspective view of the pad while having its edge inserted in a clamp applied to a wound strand of hair; and

55 Figure 3 is a view partially in cross section and partially in perspective of the pad after application to a strand of hair and of the parts of the waving apparatus associated therewith.

60 The pad shown consists of three layers or plies of material, each of rectangular shape, attached to each other along one edge.

65 The first or inner ply 1 is of a material having a high heat conductivity, a material which I find particularly well adapted for this ply being aluminum foil, although other thin metallic sheets or the like could be used. The function of this ply is to conduct heat throughout its extent and so deliver it uniformly to the entire strand of hair which it surrounds. This ply is provided with a number of perforations 2, fairly closely spaced throughout its extent, so that vapor may readily pass through it from the second ply 70 to the hair strand and may easily permeate the entire strand.

75 The second or intermediate ply 3 of the pad is of absorbent material, conveniently a fabric such as flannel, gauze, or the like, and is intended to carry the solution or one of several solutions with which the hair is to be treated. This solution may be supplied to the absorbent material by dipping the latter in the solution before applying the pad 80 to the hair, or a quantity of dried salts of the desired solution may be incorporated in the absorbent material, it being only necessary to dip the same in water, or a non-evaporative solution as one of an oily nature may 85 be incorporated in the pad during its manufacture.

90 The third or outer ply 4 of the pad is of a moisture-retaining material for which I prefer parchment, although paper or cloth which may be waxed, oiled or otherwise waterproofed, metallic foil, or other material may be used. This ply is imperforate to prevent escape of vapor when the solution is heated and to cause the same to penetrate the 95 100

hair. While this ply is shown as a separate piece of material, it may, if made of the same material as the inner ply, be formed integrally therewith and folded over, as at the attached edge or the one opposite.

The three plies are attached to each other at one edge by stitching 5, a cord 6 being laid along this edge so that it is also attached to the plies by the stitching. The cord 10 is used to produce a thickened edge by which the pad is connected to the clamp used to hold the strand of hair adjacent its roots. The pads are most conveniently made by securing together long strips of the materials 15 used along one edge and then cutting the strips up transversely into pads of the proper length. While stitching is the only securing means shown, any other desired means as staples, cement, or the like may be used.

20 The clamp illustrated is similar to that shown in the patent to Decker Number 1,683,581, issued September 4, 1928, and consists of two pivotally connected arms 7 and 8, each comprising a bar 9 of heat-insulating material and a metallic bar 10 connected thereto and spaced therefrom. The clamp is retained in closed position by an eccentric lock as shown in the above mentioned patent. A retainer consisting of a tubular 25 piece 11 slotted at 12 throughout its length is secured to the upper side of arm 7 and receives and retains the enlarged edge of the pad, the three plies of which extend through the slot, the edge of the pad being slid into 30 one end of the retainer.

The application of the pad is very simple, it being only necessary to slide the enlarged edge into the retainer of a clamp applied to a strand of hair, as illustrated in Figure 40 2, wrap the pad over the hair A upon its curler rod B with the perforated ply 1 next to the hair, as shown in Figure 3, and twist or bend each end of the pad to enclose the strand of hair. After this the heater is applied and current supplied it to heat the pad 45 and hair and so produce the desired wave.

While I have described the illustrated embodiment of my invention in some particularity, this is done by way of illustration 50 only and it is obvious that many other embodiments will readily occur to those skilled in this art, and I do not therefore limit myself to the precise details shown and described but claim as my invention all embodiments 55 coming within the scope of the appended claims.

I claim:

60 1. A multi-ply hairwaving pad comprising a perforate sheet of heat conducting material, a moisture retaining ply, and an absorbent ply intermediate said two first mentioned plies.

65 2. A multi-ply hair waving pad comprising a perforate ply of thin sheet metal, a moisture retaining ply, and an absorbent ply

intermediate said two first mentioned plies.

3. A multi-ply hair waving pad comprising a perforate ply of aluminum foil, a moisture retaining ply, and an absorbent ply intermediate said two first mentioned plies.

75 4. A multi-ply hair waving pad comprising a perforate ply of aluminum foil, an imperforate ply of parchment, and a ply of absorbent fabric intermediate said foil and parchment.

5. A multi-ply hair waving pad comprising a ply of foraminous heat conducting material, a moisture retaining ply, and an absorbent ply intermediate said two first mentioned plies, said plies being secured together 80 along one edge.

85 6. A multi-ply hair waving pad comprising a ply of foraminous heat conducting material, a moisture retaining ply, and an absorbent ply intermediate said two first mentioned plies, said plies being secured together by stitching along one edge.

90 7. A multi-ply hair waving pad comprising a ply of foraminous aluminum foil, an imperforate ply of parchment, and a ply of absorbent fabric intermediate said foil and parchment, said plies being secured together along one edge.

95 8. A multi-ply hair waving pad comprising a ply of foraminous aluminum foil, an imperforate ply of parchment, and a ply of absorbent fabric intermediate said foil and parchment, said plies being secured together by stitching along one edge.

100 9. A multi-ply hair waving pad comprising a ply of foraminous heat conducting material, a moisture retaining ply, and an absorbent ply intermediate said two first mentioned plies, said plies being secured together along one edge and this edge being thicker 105 than the rest of the pad.

110 10. A multi-ply hair waving pad comprising a ply of foraminous heat conducting material, a moisture retaining ply, an absorbent ply intermediate said two first mentioned plies, said plies being secured together along one edge, and a cord secured along said edge.

115 11. A multi-ply hair waving pad comprising a ply of foraminous sheet metal, a moisture retaining ply, an absorbent ply intermediate said two first mentioned plies, said plies being secured together by stitching along one edge, and a cord along said edge and secured to said plies by said stitching.

120 12. In combination, a hair waving pad having a thickened edge and a hair engaging clamp having a channel shaped retainer receiving and retaining said edge.

125 13. In combination, a multi-ply hair waving pad, the plies of which are secured together along one edge, which edge is thicker than the rest of the pad, and a hair engaging clamp having a channel-shaped retainer receiving and retaining said edge.

130 14. In combination, a multi-ply hair wav-

ing pad, a cord extending along one edge thereof, the cord and plies being secured together along said edge, and a hair engaging clamp having a channel-shaped retainer receiving said edge and cord and so retaining said pad in position.

15. In combination, a clamp comprising two articulated arms arranged to engage a flat strand of hair near its roots, and a pad for covering said strand during a waving operation, one of said arms having retaining means engaging and retaining one edge of said pad.

16. In combination, a clamp arranged to clamp a flat strand of hair near its roots, a multi-ply pad for covering said strand during the waving operation, the plies of the pad being secured together along one edge, and retaining means for holding said edge to one of the arms of said clamp and maintaining said edge substantially straight.

17. A hair waving pad comprising an inner perforated ply of thin sheet metal to be positioned in contact with a wound strand of hair, and a ply of absorbent material secured thereto to overlie the same when applied to said strand.

18. A multi-ply hair waving pad comprising an inner metallic layer to contact a wound strand of hair, and an outer moisture retaining layer.

19. A multi-ply hair waving pad comprising a perforated ply of aluminum foil, and an imperforated ply of absorbent material, the ply of foil being placed in contact with a wound strand of hair to be waved.

20. A hair waving pad comprising a ply of foraminous thin sheet metal to be placed adjacent a wound coil of hair.

25 40. In testimony whereof I hereunto affix my signature this 14th day of February, 1929.

PHIL. D. SPAETH, JR.
